UNITED STATES PATENT OFFICE.

GEORGE H. F. HOLY, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRIC LOCOMOTIVE.

1,317,296.

Specification of Letters Patent. Patented Sept. 30, 1919.

Application filed August 10, 1915. Serial No. 44,776.

To all whom it may concern:

Be it known that I, GEORGE H. F. HOLY, a citizen of the United States, and a resident of Pittsburgh, in the county of Allegheny and State of Pennsylvania, have invented a new and useful Improvement in Electric Locomotives, of which the following is a specification.

My invention relates to electric locomotives, and it has particular reference to the driving mechanisms therefor.

One of the objects of my invention is to provide a locomotive in which the driving motor is mounted upon a cab which is spring-supported upon the running gear, and to provide a combination of driving rods having a lost-motion connection to the driving motor, said rods being disposed in substantially the same vertical plane.

Another object of my invention is to provide a locomotive of the above-indicated character which shall be simple and rugged in construction, which shall have a relatively high center of gravity by reason of the location of the driving motor, and which, moreover, shall be adapted to transmit the driving effort thereof to the driving wheels either directly through inclined driving rods or indirectly through jack-shafts and side rods.

More specifically, it is an object of my invention to provide a simplified and improved rod drive, the arrangement of parts of which are such as to avoid the use of the usual stepped construction of crank pins and, moreover, to permit the use of identical jack-shafts and wheels and axles.

If a driving unit is mounted upon a spring-borne cab and a rod drive is employed, it becomes necessary to provide a certain degree of vertical movement between the driving mechanism and the driving motor in order to care for the movement of the cab upon the springs. Moreover, such a lost motion connection is desirable when the driving motor is mounted directly upon the running gear and jack shafts are employed, for the reason that it is practically impossible, with the present-day commercial manufacturing methods, to accurately locate the

several shafts or axles which are to be connected by the driving rods and, therefore, the rods are placed under unnecessary and

undesirable stress. Therefore it is practically essential to provide a certain amount of lost motion even with this type of motor mounting and drive.

My invention may best be understood by reference to the accompanying drawing in which Figure 1 is a view in side elevation, 55 of a portion of an electric locomotive embodying a driving mechanism constructed in accordance with my invention; Fig. 2 is a view, partially in plan and partially in section, of the upper ends of a portion of the 60 driving rods and their connection to the driving unit; Fig. 3 is a similar view of the side rods, and Fig. 4 is a view, similar to Fig. 1, of a modified form of my invention.

Referring to Fig. 1, the apparatus shown 70 comprises a running gear 1 having a plurality of sets of driving wheels 2, 3 and 4, a cab 5 resiliently carried upon the running gear 1 through springs 6, an electric driving motor 7 mounted within the cab, and a driving mechanism 8 comprising a plurality of inclined driving rods 9 and 10 and a plurality of side rods 11 and 12 by means of which the driving effort of the motor 7 is transmitted to the driving wheels. 80

The running gear 1 embodies side frames 15 of suitable construction having pedestal openings 16, 17 and 18 to receive journal boxes 19, 20 and 21 that respectively surround the axles 22, 23 and 24, in accordance with the usual practice. 85

The cab 5 is carried upon the springs 6 which are illustrated as of the elliptic type, although any form of spring support may be used, and said springs rest upon the journal boxes 19 and 21, respectively. 90

The driving motor 7 is of large capacity and is mounted upon the floor of the cab 5 and directly above the middle set of driving wheels 3. The motor may be of any construction known in the art and its shaft 27 is provided with a plurality of crank arms 28 carrying crank pins 29, said crank arms and pins being located on the respective ends of the motor shaft 27, although only the driving mechanism of one side of the locomotive is illustrated. 95

The upper ends of the driving rods 9 and 10 are both associated with the crank pins 29, and the lower ends thereof have pivotal 105 connections to the respective crank pins 31

and 32 that are severally carried by the crank arms 33 and 34 of the respective sets of driving wheels 2 and 4.

The driving rod 10 is provided, at its upper end, with an integral rectangular yoke member 36 and a pair of integral laterally projecting extensions 37. The yoke 36 is adapted to receive a bearing block 40 which is carried by the crank pin 29 and is adapted 10 for a slight vertical movement with respect to the yoke portion. The lower end of the rod 10 is also provided with a plurality of integral lateral extensions 38 for a purpose to be hereinafter set forth.

15 The driving rod 9 is disposed in the same vertical plane as the rod 10, and its upper end is interposed between the extensions 37 and pivotally secured thereto by a pin 41. The lower end of the rod 9 is provided with 20 a plurality of lateral and corresponding extensions 43, between which one end of the connecting side rod 11 is disposed and pivotally secured by a pin 44. The other end of the connecting side rod 11 has a pivotal connection with a crank pin 45 that is carried by a crank arm 46 associated with the set of driving wheels 3, while the side rod 11 projects beyond said crank pin and is provided with two extensions or arms 47 25 that straddle one end of the side rod 12 and are pivotally secured thereto by means of a pin 48. The other end of the connecting side rod 12 is interposed between the extensions 38 of the lower end of the driving rod 10 and is pivoted thereto by means of a pin 49.

By this construction of the driving and side rod mechanism, the several rods are located in the same vertical plane, whereby 40 lateral space is economized and the use of stepped crank pins avoided. Moreover, the driving effort of the motor 7 is transmitted directly to the driving wheels 2, 3 and 4 through the driving rods 9 and 10 and the 45 side rods 11 and 12, while the yoke connection between the upper end of the rod 10 and the crank pin 29 permits of a slight relative vertical movement to care for the vibrations of the cab and the inaccuracies 50 of construction.

Reference may now be had to Fig. 4, in which the electric locomotive shown differs somewhat in the arrangement of driving wheels and driving mechanism and is provided with a plurality of jackshafts 53 and 54 that are carried in bearings 55 and 56 which are disposed in pedestal openings 57 and 58 that are formed, in the usual manner, in the side frames 15. The opposite 55 ends of the respective jackshafts are provided with crank disks 59 and 60 which are severally provided with crank pins 61 and 62.

The driving motor 7 is mounted directly 65 upon the running gear 1 instead of being

carried by the cab, which may or may not be spring-borne, and the driving effort thereof is transmitted to the jackshafts 53 and 54 and to the intermediate set of driving wheels 3 through the agency of driving rods 9 and 10 and side rods 11 and 12, in the same general manner as set forth in connection with the locomotive shown in Fig. 1, a similar lost-motion yoke connection 36—40 being provided.

75 The outer sets of driving wheels 2 and 3 are mechanically associated with extensions 64 and 65 of the respective driving rods 9 and 10 by means of side rods 66 and 67 which are disposed in the same vertical plane with the other rods 9, 10, 11 and 12 and have their outer ends respectively connected to the crank arms 33 and 34 which are associated with the sets of wheels 2 and 4, respectively.

80 Thus, by means of the lost-motion rod drive mechanism set forth, a free and smooth operation is secured, which is obtained even though there be slight inaccuracies in the construction of the several 60 parts and in the location of the several rotatable shafts that are mechanically connected.

85 Obviously, my invention is not restricted to the specific structural details and arrangement and location of parts hereinbefore set forth, as modifications therein may be effected without departing from the spirit and scope of my invention, and I desire, therefore, that only such limitations 95 shall be imposed as are indicated in the appended claims.

90 I claim as my invention:

1. In a locomotive, the combination with a running-gear comprising a plurality of 105 sets of driving wheels having crank arms associated therewith, a cab spring-supported upon said running-gear, and a driving unit carried by said cab and having a crank arm, of a mechanical driving connection between the crank arm of the driving unit and the crank arms of the driving wheels comprising a plurality of downwardly diverging rods, and means associated therewith for permitting relative vertical movements between said driving unit and said mechanical driving connection in accordance with the movements of said spring-supported cab.

110 2. In a locomotive, the combination with a running-gear comprising a plurality of 120 sets of driving wheels having crank arms associated therewith, a cab spring-supported upon said running-gear, and a driving unit carried by said cab and having a crank arm, of a plurality of driving rods disposed in 115 the same vertical plane and connecting the crank arm of the driving unit with the crank arms of the respective driving wheels, and a lost-motion connection permitting relative movements between said driving unit and 130

- the driving wheels in accordance with the movements of said spring-supported cab.
3. In a locomotive, the combination with a running-gear comprising a plurality of sets of driving wheels having crank arms associated therewith, a cab spring-supported upon said running-gear, and a driving unit carried by said cab and having a crank arm, of a plurality of flexibly connected downwardly divergent driving rods disposed in the same vertical plane and joining the crank arm of the driving unit with the crank arms of the driving wheels, and means associated with one of said driving rods for permitting a vertical lost-motion connection with the driving unit crank arm in accordance with the movements of said spring-supported cab.
4. In an electric locomotive, the combination with a running-gear comprising three sets of driving wheels each provided with a crank arm, a cab spring-supported upon said running-gear, and an electric driving unit carried by said cab directly above the middle set of driving wheels and having a crank arm, of a plurality of inclined driving rods having a lost-motion connection with the driving-unit crank arm and connected to the crank arms of the outer sets of driving wheels, and a plurality of side rods operatively connecting the lower ends of the respective driving rods with the crank arm of the middle set of driving wheels.
5. In an electric locomotive, the combination with a running-gear comprising three sets of driving wheels each provided with a crank arm, a cab spring-supported upon said running-gear, and an electric driving unit carried by said cab directly above the middle set of driving wheels and having a crank arm, of a plurality of driving rods having a lost-motion connection with the driving-unit crank arm for effecting a driving connection between said crank arm and the crank arms of the outer sets of driving wheels, and a plurality of side rods pivotally associated with the ends of the respective driving rods and connected to the crank arm of the middle set of driving wheels, said driving rods and side rods being disposed in the same vertical plane.
6. In an electric locomotive, the combination with a running-gear comprising a plurality of sets of driving wheels, a cab spring-supported upon said running-gear, and an electric driving unit carried by said cab, of crank arms associated with the driving unit and the sets of driving wheels, means comprising a plurality of flexibly joined rods for connecting the crank arms of the driving unit to the respective crank arms of the driving wheels, and means for permitting a slight vertical movement between said driv-
- ing rods and the crank arm of said driving unit in accordance with the movement of 65 said spring-supported cab.
7. In an electric locomotive, the combination with a running-gear comprising a pair of rotatable shafts, and an electric driving motor disposed above said shafts and midway between them, of a driving rod between the driving motor and one of the shafts, said rod having a lost-motion connection with said motor and having a laterally-disposed extension, and a second driving 75 rod pivotally secured to said extension and to the other driving shaft.
8. In an electric locomotive, the combination with a running-gear comprising a pair of rotatable shafts, and an electric driving 80 motor disposed above said shafts and midway between them, of a crank arm and crank pin associated with the driving motor, a bearing block carried by said pin, a driving rod connected to one of said rotatable shafts and having its upper end provided with a yoke to receive said bearing block and with a lateral extension, and a second driving rod connected to said extension and to the remaining rotatable shaft. 90
9. In an electric locomotive, the combination with a running-gear comprising a plurality of sets of driving wheels, a plurality of jackshafts, and a driving unit mounted upon said running-gear, of a plurality of 95 driving rods having a lost-motion connection with the driving unit and mechanically connected to the jackshafts, and a plurality of side rods between said jackshafts and the sets of driving wheels. 100
10. In an electric locomotive, the combination with a running-gear comprising a plurality of sets of driving wheels, a plurality of jackshafts disposed intermediate said sets of wheels, and an electric motor mounted upon said running-gear, of a plurality of driving rods having a vertical lost-motion connection with said driving motor and connected to the respective jackshafts, and a plurality of side rods associated with the 110 driving rods and connected to the driving wheels, said driving rods and side rods being disposed in the same vertical plane. 105
11. In an electric locomotive, the combination with a driving unit having a crank pin attached thereto and a plurality of sets of driving wheels, of two driving rods having a lost-motion connection to said crank pin, two jack shafts joined to said driving rods and side rods for connecting the driving wheels to said jack shafts. 115
- In testimony whereof, I have hereunto subscribed my name this 31st day of July, 1915.

GEORGE H. F. HOLY.
